UNITED STATES PATENT OFFICE.

THOMAS H. WILSON, OF BRAWLEY, CALIFORNIA.

PLANT PROTECTOR.

Application filed February 11, 1926. Serial No. 87,574.

This invention relates to improvements in plant protectors.

An object of this invention is to provide a protector for plants which is so constructed as to effectively prevent the plant from frost and which will retain the heat to a certain extent, enabling young plants to be set out during cold weather and promoting the growth of the plant, causing it to mature sooner.

Another object of this invention is to provide a plant protector which may be easily, quickly and cheaply constructed, and which is capable of being knocked down to facilitate shipping and storing.

With the foregoing and other objects in view which will be made manifest in the following detailed description and specifically pointed out in the appended claims, reference is had to the accompanying drawings for an illustrative embodiment of the invention, wherein:

Figure 1 is a perspective view of the improved plant protector from the open side, shown in set-up position,

Fig. 2 is a side elevation of the same,

Fig. 3 is a plan view of the blank from which the protector is formed,

Fig. 4 is a sectional view taken on the line 4-4 of Fig. 1, and

Fig. 5 is a view illustrating a manner in which the plant protector is used.

Referring to the accompanying drawings wherein similar reference characters designate similar parts throughout, the improved plant protector is formed of a section of bendable sheet material, such as cardboard. This cardboard is preferably made insect-proof and water-proof by coating it with a solution of copper aluminum formate or equivalent insecticide and by dipping it into melted parafine or similar water-proofing substance. The reference character 10 indicates what may be considered as the center or apex forming portion of the blank. The blank is illustrated as having parallel top and bottom edges 11 and 12 respectively, the bottom edge being rounded up slightly adjacent its ends, as at 13. The side edges 14 are upwardly convergent and are slightly arcuate.

The blank is preferably embossed to form a reinforcing rib 15 which extends around the bottom and side edges, and additional reinforcing ribs 16 are also formed upon the blank which extend approximately in a ra-

dial direction from the apex 10. A horizontal reinforcing rib 17 is also formed by embossing the blank, this horizontal rib connecting the rib 15 and crossing the ribs 16. Immediately above the horizontal rib 17 there are positioned a plurality of ventilating apertures 18, and adjacent the top edge 11 there are formed apertures 19 adapted to receive fastener parts 20. These fastener parts may be in the form of small metallic rivets or paper fasteners, and it is desirable that these fasteners be readily removable, so that the blank can be knocked down for storing or shipping and can be easily set up again. Adjacent the lower corners of the blank there are also formed apertures 21 for a purpose to be hereinafter more fully described.

The plant protector is formed by bending the blank shown in Fig. 3 into the position as shown in Figs. 1 and 2, and the fasteners 20 are inserted through the apertures 19 of the overlapping edges 11 at the top of the blank. In this manner the blank is caused to form a conical structure having an open side, which open side extends from a point below the apex or top of the cone to the bottom. The reinforcing ribs 15, 16 and 17 serve to stiffen the cardboard blank, but at the same time permitting its bending without breaking the fibers of the cardboard.

In use the plant protector is placed on the ground over the plant P in such a manner that the apex is almost directly above the plant. It is so arranged that the open side or the opening through the conical structure is exposed toward the south, thus permitting sunshine to strike the plant through the opening. At the same time the back of the protector effectively protects the plant from cold north winds. The overlapping edges 11 form a closed conical structure adjacent the apex of the plant protector and cause a dead air space to be formed to a greater or less degree adjacent the top of the protector. This air space serves as a heat retaining space and tends to keep the interior of the protector warm. In actual practice it will be found that the temperature within the protector is from 4 to 8° F. higher than the temperature of the surrounding atmosphere. The small apertures 18 enable a very slight draft or circulation of air through the protector so that cold air will not be entrapped therein. In positioning the protector over the plant, its

lower edges are preferably thrust into the ground, as indicated in Fig. 5; or, if desired, the lower edges may merely rest on top of the ground. In either case, if it is desired to prevent the protector from being blown over by the wind, small stakes or strips of lath can be driven through the apertures 21 and into the ground so as to hold the protector in place. Because of the arrangement of the side edges 14, it will be noted that the plant is exposed to the morning sun, the afternoon sun and also the noon-day sun.

From the above described construction it will be noted that the blank is water-proof and will not be damaged by rain or mildew, and that insects will not attempt to eat the blank because of the coating of insecticide. The coating of insecticide also tends to keep the insects away from the plant. The protector is primarily designed to be used in connection with young plants, and when danger of frost is past, it is intended that it be removed. In such instances the fasteners 20 can be pulled out and the complete blank caused to assume its knocked down position, as shown in Fig. 3, permitting a large number of the protectors to be stacked and stored in a small amount of space.

It will be understood that various changes in the detail of construction may be made without departing from the spirit or scope

of the invention as defined by the appended claims.

I claim:

1. A plant protector comprising a blank of bendable sheet material bent to form a cone, the meeting edges of the blank being cut away providing an opening in the cone extending from its bottom to a point some distance below the apex of the cone, and means for securing the meeting edges of the blank together from the mentioned point to the apex so as to provide a heat retaining air space as and for the purpose described, 45 said blank having embossed portions providing reinforcing ribs, some of which extend downwardly from the apex and others extending horizontally about the cone.

2. A plant protector comprising a blank 50 of bendable sheet material bent to form a cone, the meeting edges of the blank being cut away providing an opening in the cone extending from its bottom to a point some distance below the apex of the cone, and 55 means for securing the meeting edges of the blank together from the mentioned point to the apex so as to provide a heat retaining air space, there being apertures formed in the lower corners of the blank as and for 60 the purpose described.

In testimony whereof I have signed my name to this specification.

THOMAS H. WILSON.
